SPIKE SETTER CARRIAGE

Knox Kershaw and Royce Kershaw,
Montgomery, Ala.

Application September 6, 1946, Serial No. 695,076

1 Claim. (Cl. 105—144)

1

This invention relates to a carriage for use in setting railroad spikes to be later driven home by means of mechanical spike drivers or other means, and has for an object the provision of apparatus of the character designated which shall be propelled by the operator pushing on the ground with his feet and on which there is carried a supply of railroad spikes within his easy reach.

A further object of our invention is to provide a carriage of the character designated which shall include an operator's seat and a spike storage bin so situated that the operator is in position to set the spikes with a small hammer, straight and true, for final driving.

A still further object of our invention is to provide a carriage for use in setting railroad track spikes whereby the arduous physical labor usually associated with such work may be greatly reduced.

As is well known in the art to which our invention relates, the setting and driving of railroad track spikes has heretofore involved a great amount of extremely hard physical labor. It has heretofore been the practice to assign one workman to carry and distribute spikes along the track, another workman to set and hold the spikes, and two other workmen with sledges to drive the spikes home. By means of our invention, the manual labor involved can easily be accomplished by one workman. Our invention embodies a relatively light carriage which may be readily lifted on and off the railroad track. Included in the carriage is a main frame having tandem double flanged supporting wheels riding on one rail of the track and having an operator's seat on one end and a storage bin for railroad spikes on the other end, facing the operator. A discharge gate for the spikes is within ready reach of the operator and from this gate he withdraws the spikes, sets and starts them with a small hammer while in a sitting position. Sockets are provided on both sides of the main frame for detachably connecting a transverse frame member which carries a flangeless wheel which rides on the opposite rail of the railroad track. By this means, the carriage may be mounted on either rail of the track, and propelled by the operator in the same direction.

Apparatus embodying features of our invention is illustrated in the accompanying drawing, forming a part of this application, in which

Fig. 1 is a plan view thereof;

Fig. 2 is a side elevation, partly in section;

Fig. 3 is an end elevation showing the carriage on one rail of the track; and

2

Fig. 4 is a similar view showing the carriage on the opposite rail of the track and the transverse member connected to the opposite side of the main frame.

Referring now to the drawings for a better understanding of our invention, we show a railroad track embodying rails 10 and 11 and cross ties 12. Mounted on the track is our improved carriage which comprises a relatively long main frame 13 which may be constructed of any suitable material such as standard, rolled steel shapes, pipe, or other known structural forms which provide strength with light weight. The carriage 13 is supported by tandem double flanged wheels 14 and 16 having axles 17 and 18 which are journaled in the main frame.

Joined to the main frame 13, on opposite sides thereof, are two socket members 19 and 21 which may conveniently be made of short sections of pipe welded to the main frame. A transverse frame member 22 is adapted to fit in either of the sockets 19 or 21 and be secured thereto by means of bolts or other suitable fastening means 23. The transverse frame member 22 has journalled on its outer end a flangeless wheel 24, or roller, which rests on the opposite rail 11 of the railroad track. As shown in Figs. 1 and 3, the main frame 13 with its supporting wheels 14 and 16 is mounted on the rail 10. By detaching the transverse frame member 22 and inserting it in the socket 19, the carriage may be mounted on the rail 11 without being turned around.

Mounted on one end of the main frame 13 is an operator's seat 26 which is made relatively low, as shown in Fig. 2, whereby a workman sitting on the seat, is not required to bend over an undue amount in accomplishing his task. On the opposite end of the main frame 13, facing the operator's seat 26 is a spike storage bin 27 which may conveniently be made up of structural steel angles and plates. The storage bin is provided with a sloping bottom 28 which delivers the spikes in the bin to a discharge gate 29 within easy reach of a workman on the operator's seat 26.

In operation, a workman seated on the seat 26, as shown in Fig. 2, pushes the carriage backward by means of his feet engaging the ground alongside the main frame. As the carriage is pushed backwards, the workman reaches the spikes in the discharge gate 29, sets them and starts them by means of a small sledge hammer 30, as shown in Fig. 2. After the spikes have been set for the required distance on rail 10, the carriage is returned, the main frame with its wheels 14 and 16 is placed on the rail 11, the transverse frame

member 22 is removed from the socket 21 and placed in the socket 19, as shown in Fig. 4, and the workman then sets the spikes along the opposite rail 11. After the spikes have been set as described they are driven home by a mechanical spike driver, not shown, or other suitable means.

From the foregoing, it will be apparent that we have devised an improved means for setting railroad track spikes which is simple and sturdy of construction and which serves to reduce greatly the manual labor involved in this operation.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are specifically set forth in the appended claim.

What we claim is:

A carriage for use in setting railroad track spikes comprising a relatively narrow main frame adapted to be straddled by an operator and having tandem double flanged supporting wheels of relatively small diameter on one rail of the track, a transversely extending socket on each side of the main frame, a transverse frame member adapted to fit in either socket, a wheel carried by the outer end of the transverse frame member adapted to rest on the opposite rail of the track, 30

an operator's seat on one end of the main frame over one of the supporting wheels and of such height that when seated thereon, the operator's feet are in engagement with the ground in position to propel the carriage, a spike storage bin on the other end of the frame, spaced from the seat and having a discharge opening therein in easy reach of a workman on the operator's seat and affording an uninterrupted space in which to manipulate a spike setter's hammer, and a sloping bottom in the storage bin for delivering the spikes to the discharge opening.
